UNITED STATES PATENT OFFICE.

HARRY BRANDEN, OF TRAVERS, ALBERTA, CANADA.

GRINDING APPARATUS.

Application filed May 2, 1921. Serial No. 463,017.

To all whom it may concern:

Be it known that I, HARRY BRANDEN, a citizen of the Dominion of Canada, residing at Travers, in the county of Bow River and 5 Province of Alberta, have invented certain new and useful Improvements in Grinding Apparatus, of which the following is a specification.

The present invention relates to improvements in grinding apparatus and the principal object is to provide a device of the character described, adapted for grinding discs.

A further object is to provide means whereby the disc being ground will be tensioned against the emery wheel positioned on the apparatus.

With these and other objects in view, the invention consists in the construction, combination and arrangement of parts, as will be hereinafter fully described, illustrated in the accompanying drawings and pointed out in the claims hereunto appended.

Figure 1 is a side elevational view, illustrating my improved grinding apparatus.

Fig. 2 is a top plan view of the same.

Fig. 3 is an end elevational view of the same.

Referring to the drawings, like numerals 30 designate like parts in the various drawings.

The numerals 4 and 5 indicate the standards supporting the apparatus. Transverse bars 6, 7 and 8 are longitudinally disposed on the standards and substantially connected 35 thereto.

Transverse shaft 9 is journaled in bearings 10 and 11 on the upper extremity of standards 4 and 5. A suitable platform 12 is positioned on the transverse bars 6 and 7 40 and supports an electric motor 14. Power is transmitted from the motor to the transverse shaft 9 by belt 15 trained over pulleys 16 and 17 positioned on the drive shaft of the motor and the said transverse shaft 9.

45 The bar 8 has a longitudinal slot 18 and has a bolt 19 passing through the same to engage in the longitudinal slot in the transverse bar 20 on the bracket member 21. This transverse bar 20 is slidably mounted 50 in the guide 22, in the bar 8. Bracket member 21 supports the vertical sleeve member 23, in which is journaled vertical shaft 24. Helical gear 25 is mounted on the lower end 55 of the vertical shaft 24, and is rotated by worm gear 26 mounted on transverse shaft 27, which is journaled in bearings 28, 29

and 30. Bearings 28 and 29 are on the bracket member 31 mounted on the vertical sleeve member 23. Bearing 30 is on standard 22, the lower end of which is mounted 60 on the end of transverse bar 7. Pulley wheel 33 is mounted on the end of transverse shaft 27 and is driven by belt 34 trained over it and pulley 35 mounted on the transverse shaft 9.

To tighten belt 34, a transverse rod 36 is connected to standard 32 and passes through an aperture in the transverse bar 37, where it is regulated by nut 38 by adjustment of which the belt may be tightened. To permit 70 lateral movement of the transverse shaft 27, I provide a suitable universal joint indicated at 39. Emery wheel 40 is mounted on the end of the transverse shaft 9 and to prevent reciprocation of the said shaft, I 75 provide collars 41 and 42, which are secured to the same at the opposite sides of the bearings 10.

The upper end of the vertical shaft 24 is adapted for detachably mounting a disc on 80 the same. A roller 43 is rotatably mounted on bracket 44 and rotates on the upper face of the disc while the same is being sharpened. The said roller being tensioned downwardly by the spring 45 secured to the bearing 10 85 and bracket 44, which bracket is hingedly mounted on standard 46 on the bearing 10.

In use, the sleeve and bracket members are moved back and forth for changing the discs. When it is desired to hold the same 90 in stationary position, the nut positioned on bolt 19 may be tightened.

From the foregoing, it is thought that the construction of my invention will be clearly understood, and, therefore, a more extended 95 explanation has been omitted.

What I claim as new is:

1. An apparatus of the character described, comprising in combination supporting standards, bearings on the said supporting standards, a main transverse shaft journaled in the said bearings, means to rotate said shaft, upper and lower transverse bars mounted on the said supporting standards, a slideable bracket on the upper transverse bar, a sleeve vertically mounted in the said bracket, a vertical shaft journaled in the said sleeve, means for mounting a disc on the upper end of the said vertical shaft, an emery wheel mounted 105 on the said main transverse shaft, means 110 rotating the said disc in proper ratio with

the said emery wheel, and means for yieldingly holding the said disc on the said emery wheel.

2. An apparatus of the character described, comprising in combination supporting standards, bearings, on the said supporting standards, a main transverse shaft journalled in the said bearings, means to rotate the said shaft, upper and lower transverse bars mounted on the said supporting standards, a bracket, means slidably mounting said bracket on the upper transverse bar, a sleeve vertically mounted in the said bracket, a vertical shaft journalled in the 10 said sleeve, means for mounting a disc on the upper end of the said vertical shaft, an emery wheel mounted on the said main transverse shaft, means rotating the said disc in proper ratio with the said emery wheel, said means comprising a helical gear positioned on the said vertical shaft, a bracket mounted on the said sleeve, bearings on the said bracket, a secondary transverse shaft journalled in the said bearings, a worm 15 mounted on the said transverse shaft functioned to drive the said helical gear, an upright standard mounted on the said frame, a bearing on the said standard, the opposite end of the said secondary transverse shaft journalled in the 20 said bearing, a pulley mounted on the said secondary transverse shaft, and a pulley mounted on the said main transverse shaft, a driving belt trained over the said pulley and pulley wheel, a pivoted bracket, a roller carried 25 thereby for contact with the disc being ground and a spring acting on said bracket between its pivot and the roller to hold said roller in contact with the disc.

40 3. An apparatus of the character described, comprising in combination support-

ing standards, bearings on the said supporting standards, a main transverse shaft journalled in the said bearings, means to rotate the said shaft, upper and lower transverse 45 bars mounted on the said supporting standards, means slidably mounting a bracket on the upper transverse bar, a sleeve vertically mounted in the said bracket, a vertical shaft journalled in the said sleeve, 50 means for mounting a disc on the upper end of the said vertical shaft, an emery wheel mounted on the said main transverse shaft, means rotating the said disc in proper ratio with the said emery wheel, said means 55 comprising a helical gear positioned on the said vertical shaft, a bracket mounted on the said sleeve, bearings on the said bracket, a secondary transverse shaft journalled in the said bearings, a worm mounted on the 60 said transverse shaft functioned to drive the said helical gear, an upright standard mounted on the said frame, a bearing on the said shaft, the opposite end of the said secondary transverse shaft journalled in the 65 said bearing, a pulley mounted on the said main transverse shaft, a driving belt trained over the said pulley and pulley wheel functioned to transmit power from the said pulley to the said pulley wheel and means 70 regulating the tension of the said belt, a pivoted bracket, a roller carried thereby for contact with the disc being ground and a spring acting on said bracket between its 75 pivot and the roller to hold said roller in contact with the disc.

In testimony whereof, I hereunto affix my signature in the presence of two witnesses.

HARRY BRANDEN.

Witnesses:

PETER BRANDEN,
HORACE W. WRIGHT.
